UNITED STATES PATENT OFFICE.

CHARLES N. WAITE, OF WILMINGTON, DELAWARE.

METHOD OF DISCHARGING PULP-DIGESTERS.

953,076.

Specification of Letters Patent. Patented Mar. 29, 1910.

Application filed May 14, 1908. Serial No. 432,773.

To all whom it may concern:

Be it known that I, CHARLES N. WAITE, a citizen of the United States of America, residing in Wilmington, in the county of Newcastle and State of Delaware, have invented a certain new and useful Improvement in Methods of Discharging Pulp-Digesters, of which the following is a true and exact description, reference being had to the accompanying drawings, which form a part thereof.

In the manufacture of the so-called "soda pulp" it is the common practice to employ an upright digester in which the wood chips or like pulp forming material is cooked for several hours at such a temperature and under such conditions that a steam pressure of about 120 lbs. is maintained in the digester. When the pulp forming material has been sufficiently cooked a discharge orifice at the lower end of the digester is opened and the pulp is discharged into a chamber ordinarily called the "blowpit", by the pressure of the steam on the upper end of the digester on the mass of pulp and cooking liquor in the lower end of the digester. The pressure in the "blowpit" is usually maintained approximately equal to the pressure of the atmosphere and the success of the pulp forming operation depends in part on the disintegration of the pulp which occurs when the pulp enters the blowpit, and is due to the conversion into a steam of the cooking liquor with which the pulp is saturated. This conversion into steam is of course due to the fact that the pressure in the blowpit is far below the steam pressure corresponding to the temperature of the liquor in the pulp when it enters the blowpit.

Heretofore difficulty has been experienced in the operation of discharging pulp digesters as above described from the fact that all of the pulp does not always pass out of the digester with the cooking liquor, a portion of the pulp frequently adhering to or lodging against the lower wall of the digester. This is objectionable since the portion remaining prevents the proper amount of fresh chips or like pulp forming material from being put into the digester at the following charging operation and because the portion of the charge which is twice cooked is injured by the second cooking operation.

The object of the present invention is the

provision of a simple and effective method by which the digester may be thoroughly cleaned and emptied during each discharge operation without interfering with the maintenance of the proper steam pressure in the digester to force out the cooking liquor and pulp and to disrupt the latter in the blowpit, and without appreciably diluting the used cooking liquor or otherwise making it more difficult to recover the valuable chemical constituents of such liquor.

In carrying out my invention I provide a tank or like closed receptacle having a valved discharge connection leading from its bottom into the digester and having a steam inlet or supply connection from a suitable steam supply source. This receptacle I partially fill with the "black liquor" i. e., waste liquor from previous pulp cooking operations. I put the liquor in the tank under a steam pressure approximately equal to the working pressure in the digester and heat the liquor to a corresponding pressure. When the digester is to be discharged, and usually after the discharge operation is started, I empty liquor from the tank into the digester. By proceeding in this manner I am able to introduce liquor into the digester to work out of it all the pulp at each discharge operation. As the liquor in the tank is heated to or above the temperature then existing in the digester it does not tend to condense the steam in the digester and serves in the blowpit to disrupt the pulp which is carried out with it.

The various features of novelty which characterize my invention are pointed out with particularity in the claims annexed to and forming a part of this specification. For a better understanding of the invention, however, and the advantages possessed by it, reference may be had to the accompanying drawings and descriptive matter in which I have illustrated one method by which the invention may be carried out and one form of apparatus which may be used in carrying out the invention.

The drawing is a diagrammatic elevation of a portion of a pulp making plant equipped with my invention.

In the plant shown by the drawing there are a series of similar digesters A of which two are shown. Each of the digesters A opens at its lower end to a common discharge pipe when the corresponding cock or valve B is opened. Each digester may be

charged at its upper end when the manhole cover A' is removed. Pipe C leads to the blowpit or chamber D open at its upper end through large pipe D' to the atmosphere. A pipe D² leading from the lower end of the blowpit carried the liquor and pulp to a wash pit E, which has a screen or strainer E². A liquid discharge pipe E' leads from pit E to the black liquor reservoir F. A pump and pipe connections F', G', G² and G⁴ serve to carry such of the black liquor from reservoir F as is needed either to the upper end of blowpit D to wash down the pulp in it or into the tank H accordingly as valves G³ and G⁵ are set.

The tank H has leading from its lower end a discharge pipe H' having in it a cock H² and connected to a distribution pipe H³ from which runs branches H⁴ controlled by cocks H⁵ to the various digesters A. The tank H is provided with steam gage H⁷, blow off cock H⁶, safety valve H⁸ and water glass H⁹. A steam supply pipe I leads into the tank H and has a perforated portion I² extending along the bottom of the tank. A valve I' controls the admission of steam into the tank H through pipe I from a suitable source of steam supply not shown.

The chips or other pulp forming material is admitted to each digester through the door or manhole formed in its upper end, and normally closed by the cover A'. The cooking liquor is admitted in any suitable manner.

The digesters may be heated externally or internally by blowing steam into them. Similarly the black liquor in the tank E may be heated solely by steam admitted through pipe or by steam heating coils or in any other suitable manner.

To fill the tank H the valve I is closed and the blow off cock H⁶ is opened to permit the steam in the tank to pass out. The valve G⁵ is then opened and valve G³ is closed. The pump G then forces the waste liquor from reservoir F into the tank H. When the tank contains the desired amount of liquor the valves or cocks G⁵ and H⁶ are closed. The valve I' is then opened and the desired pressure and temperature conditions in the tank H are created. In practice I usually build the pressure in the tank H. to something less than the minimum cooking pressure in the digester A. If the latter is 120 pounds I make the pressure in the tank H about 110 pounds.

In discharging a digester A, I first open the cock B and wait until the pressure in the digester has fallen somewhat below the pressure in tank H, then I open the appropriate valve H⁵ and admit liquor from tank H into the digester A. A baffle plate A² or other spreading device may be located in the digester to cause the liquor to be properly distributed. The liquor thus admitted serves

to wash out the digester and carry with it into pipe C all the pulp in the digester. On account of its temperature it does not tend to condense the steam in the digester, but on the contrary assists in maintaining the desired steam pressure in the digester. The heat in the liquid admitted to the digester will cause a portion of the liquid to be converted into steam when the pressure on the liquid is reduced. By proceeding in this manner a sufficient steam pressure can be maintained in the digester until all the pulp is discharged whereupon the valve H⁵ is closed.

As the waste liquor admitted from tank H is substantially identical with the cooking liquor in the digester, save for some dilution which may occur from condensation of steam admitted through pipe I, the use of the flushing liquor does not interfere with, or increase the difficulty of recovering the valuable chemical constituents of the waste liquor. These constituents may be recovered by drawing off the surplus liquor from reservoir F, evaporating and burning the residue in the usual manner.

An important advantage of the apparatus described is had from the fact that the pressure, as well as the temperature of the black liquor, is built up in tank H in a very simple manner by the direct action of steam under pressure. While a pump such as pump G working against a head of only a few feet is quite satisfactory, it is very difficult to pump the waste liquor, even if cold, against the head necessary to cause it to enter the digester on account of the changing pressure in the discharging digester, and corrosive nature of the waste liquor, and because it always contains considerable amounts of pulp fibers.

Having now described my invention, what I claim as new and desire to secure by Letters Patent, is:

1. The method of removing pulp from a pulp digester which consists in employing the direct pressure of steam to blow into the digester black liquor heated to a temperature corresponding to a steam pressure not less than the pressure in the digester. 115

2. The method of removing pulp from a pulp digester, which consists in blowing black liquor into the digester by the direct action on the black liquor of steam of a pressure not less than the pressure in the digester, whereby the black liquor introduced into the digester is heated before introduction to a temperature at least as high as the temperature in the digester, and the black liquor does not lower the pressure in the digester. 120 125

CHARLES N. WAITE.
